UNITED STATES PATENT OFFICE.

ARTHUR HALLIWELL, OF DENVER, COLORADO.

DESIGN FOR A COMBINED LAMP AND SUPPORTING BRACKET FOR AUTOMOBILE FENDERS.

Application filed April 12, 1927. Serial No. 21,555. Term of patent 14 years.

To all whom it may concern:

Be it known that I, ARTHUR HALLIWELL, a citizen of the United States, residing in the city and county of Denver, State of Colorado, have invented a new, original, and ornamental Design for a Combined Lamp and Supporting Bracket for Automobile Fenders, of which the following is a specification, reference being had to the accompanying drawing, forming part hereof.

Fig. I is a top plan, Fig. II is the side elevation, Fig. III is a bottom view and Fig. IV is a front elevation.

I claim—

The ornamental design for a combined lamp and supporting bracket for automobile fenders, as shown.

ARTHUR HALLIWELL.
